UNITED STATES PATENT OFFICE

MICHAEL A. EIBEN, OF CLEVELAND, OHIO

RAPPING MACHINE FOR DUST COLLECTORS

Application filed October 29, 1927. Serial No. 229,673.

The purpose of this invention is to provide a mechanical means for rapping the screens of a dust collector apparatus and which will effectively rap the screens without any attention on part of the worker.

One of the important objects of the invention is that by the means of this machine each and every screen in the dust collector apparatus receives a thorough rapping the advantage of which is quite obvious.

In the accompanying drawings Fig. 1 is a general view of a dust collecting device or apparatus equipped with a traveling rapping for shaking the collected dust material off the screens. Fig. 2 is a longitudinal section thru the rapping device. Fig. 3 is a section on line 3—3 of Fig. 2. Fig. 4 is a section on line 4—4 of Fig. 2. Fig. 5 is a perspective view of an assembled cam shaft. Fig. 6 is a simplified diagram of the electrical connections.

Referring specifically to the drawings 1 is an electric motor which is connected through suitable reducing gear to the axle 3 as shown in Fig. 2. Said speed reduction may conveniently be accomplished as shown by means of a spur gear 4 mounted on motor shaft 5 and meshing with an internal gear 6 upon the exterior of which are located the threads of a worm 7. The said worm 7 in turn meshes with and drives a worm gear 8 secured to above mentioned axle 3. Said axle 3 has mounted securely thereon the driving wheels 9 as shown in Fig. 4. These driving wheels 9 as shown are provided with a multiplicity of driving pins 10 adapted to engage with a series of holes 11 in the rail 12 upon which the rapping device is arranged to travel. See Fig. 1. Upon reaching predetermined points at each end of its travel upon said rails 12 the rapping device engages with the trip lever 13 on rock shaft 13^a of limit switch 14, which parts are duplicated at each end of the track, by means of which the electric connections to the motor are reversed, causing the rapping device to stop its travel in one direction and proceed in the opposite direction automatically. The electrical connections are conventional and any suitable kind of reversing switches may be used.

The electric motor 1 and gearing in connec-

tion therewith are mounted in a housing or casing 15 which may conveniently be closed dust-tight by the cover plates 16 and 17.

Said electric motor 1 also has mounted upon the shaft 5 thereof on the opposite end from gear 4 a bevel pinion 18. Upon the opposite sides of said bevel pinion 18 are meshed the bevel gears 19 and 19' free to rotate on the shaft 23 which by reason of their location will be driven in opposite directions by the rotation of said bevel pinion 18. Furthermore, upon the reversal of the direction of rotation of the motor 1 as above explained the direction of rotation of said bevel gears 19 and 19' will likewise each be reversed whereby it will be seen that in either event one of said bevel gears 19 and 19' will be rotating in such direction that the one of the pawls 20 mounted on each will engage with the notch 21 in one of the ratchets 22 adjacent thereto and cause said ratchet 22 and the cam shaft 23 to which ratchet 22 is attached to revolve always in the same direction. It will be seen that when the pawl 20 on one bevel gear 19 or 19' is driving the cam shaft 23 the pawl 20 on the other bevel gear 19 or 19' is riding free over the ratchet 22 adjacent thereto.

It will be noted that the pawl 20 may be conveniently held against the ratchet 22 by means of a spring 24. The cam shaft 23 carries in addition to ratchets 22 a cam 25 which impinges upon a button 26 attached to the arm 27 of a rapping rod 28 slidably mounted in the housing 15. Said rapping rod 28 is attached to a rapping head 29 or hammer which may conveniently be provided as shown with a replaceable rapping block 30. A spring 31 is interposed between the housing 15 and the rapping head 29 to actuate the blow delivered by the rapping pad 30 at each release by the cam 25. A further dust exclusion for the joint where the rapping head 29 emerges from the housing 15 is conveniently made by a sleeve 31^a of flexible material secured by wires 32 to said rapping head 29 and housing 15.

By the means above explained it will be seen that the rapping pad 30 is caused to make a succession of blows against the dust arrester screens 33 under which the rapping device is traveling.

By this construction it is possible to have one standard size of rapping device which is applicable to any length assembly of dust arrester screens.

5 I claim:

1. A rapping machine for dust arresters or the like having a series of screens, comprising a reciprocating carriage movable across the screens, a motor mounted on the carriage, a rapping device carried by the carriage, and a connecting mechanism to said device actuated by the motor to rap the screens.

2. A rapping machine as set forth in claim 1, the motor having driving connections to the carriage.

3. A rapping machine as set forth in claim 1, the motor having driving connections to the carriage, and means to automatically reverse the movement of the carriage at a limit of travel in either direction.

4. A rapping machine as set forth in claim 1, the motor being reversible and having driving connections to the carriage, and means to automatically reverse the motor at a limit of travel of the carriage in either direction.

5. The combination with a dust arrester having a series of screens, of a rapping machine comprising a carriage movable across the screens, a motor carried thereby, a hammer mounted on the carriage and arranged to strike the screens, and operating connections between the motor and the hammer.

6. The combination with a dust arrester having a series of screens, of a rapping machine comprising a carriage movable across the screens, a motor carried by the carriage, a spring-operated hammer mounted on the carriage and arranged to strike the screens, and a trip mechanism operated by the motor and operating on the hammer to retract the same against the tension of the spring.

7. The combination with a dust arrester having a series of screens, of a rapping machine comprising a wheeled casing movable across the screens, a motor in the casing, geared to the wheels, a trip hammer carried by the casing and arranged to strike the screens, and trip mechanism operated by the motor to retract and release the hammer.

8. The combination with a series of screens, of a track extending across the same, a wheeled casing traveling thereon, a reversible motor in the casing, driving gearing between the motor and the wheels, a trip hammer carried by the casing and arranged to strike the screens, trip mechanism operated by the motor, to retract and release the hammer, and means to automatically reverse the motor at the end of the track.

9. The combination with a series of screens, of a rapping machine comprising a casing movable across the screens, a spring-actuated trip hammer mounted thereon and arranged to strike the screens, a motor in the

casing, and a trip mechanism driven by the motor, including a shaft provided with a cam engaging the hammer to retract and release the same.

10. The combination with a series of screens, of a rapping machine comprising a casing movable across the screens, a spring-actuated trip hammer reciprocating therein, a reversible motor in the casing, and a trip mechanism driven by the motor and including selective pawl and ratchet devices adapted to trip the hammer in either direction of rotation of the motor.

In testimony whereof, I do affix my signature.

MICHAEL A. EIBEN.
